METHOD OF AND MEANS FOR MANUFACTURING BRICKS

Original application filed May 28, 1928, Serial No. 281,018. Patent No. 1,773,827, dated August 26, 1930.
Divided and this application filed May 18, 1929. Serial No. 364,021.

This application is a division of my pending application Serial No. 281,018, filed May 28, 1928, now patent No. 1,773,827 August 26, 1930.

The present invention relates to the manufacture of brick, and more particularly to the means for receiving unit piles of bricks and for guiding formation of the piles to the end that one or more transverse arches may be formed in the unit piles. While the specific device is shown as a transfer or drying car, the invention is not to be limited to that specific embodiment.

In hacking the bricks onto the cars, known as transfer or drying cars, as disclosed in my prior application, certain difficulties were encountered in alining the bricks to form the arches, and this difficulty I overcome, by providing guides for defining the arches, these guides, however, being so designed as not to interfere with the use of the automatic lifting forks employed for lifting and transporting unit piles of bricks.

These guides are also designed to prevent the fingers of the lifting fork from becoming caught when the tines of the fork are inserted into the openings left in the bottom of the unit pile for that purpose.

The guides are preferably mounted upon base plates shiftable laterally on the car for the purpose of permitting better access of the hot gases in the drying oven or dryer, the plates with their superposed piles of brick being moved together to form a unitary pile at the time that the fork is to be inserted.

When the piles have passed through the dryer and been consolidated and taken up by the fork, they are then placed in position in the kiln, and the kiln is built up with arches of green brick of a single brick-length in width extending from side to side of the kiln. The kiln is scoved in any preferred manner, as for example, by smearing over the surface along the sides and ends a mixture of brick dust and water, or brick dust clay and water, burners are inserted at each end of each arch and burning is then begun. Preferably, but not necessarily dog houses or small tubular extensions of the arches formed of burned bricks are employed so as

to bring the fire from the burner nozzles out nearer to the outside surface of the kiln. Obviously, removable scoving having suitable restricted openings for communicating with the ends of the arches may be employed if desired. Firing is carried on from each end of the arches, and the object of the firing is, of course, to burn the bricks, and this is accomplished most effectively by filling the arches from end to end with fire from the burners.

Due to the relatively large ratio of escape openings between bricks to the volume defined by the arch, the burning is much more rapid and satisfactory and results in less slagging or melting of the bricks in the arches than has been thought possible prior to my invention.

While preferably open clamp kilns are employed in this method of burning brick, and I shall describe a specific embodiment employing the same, there are certain features of my invention which may be employed in the manufacture of brick regardless of the kind of kiln employed. The kiln, its method of formation and burning are disclosed in my prior copending Patents Nos. 1,757,786 and 1,790,882.

Now in order to acquaint those skilled in the art with the manner of constructing and operating a device embodying my invention and practicing my process, I shall describe in connection with the accompanying drawings a typical layout including the dryer car, the kiln and the intermediate apparatus.

In the drawings

Fig. 1 is a side elevational view of a dryer or transfer car embodying my invention.

Fig. 2 is a plan view of the same.

Fig. 3 is a cross sectional view taken on the line 3—3 of Fig. 2.

Fig. 4 is a perspective view of one of the base plates with a spring guard or guide thereupon.

Fig. 5 is a side elevational view of the lifting fork showing the mounting turntable thereof in section.

Fig. 6 is a fragmentary sectional view taken on the line 6—6 of Fig. 5 and showing

some of the pickup bricks between the tines of the fork.

Fig. 7 is a top plan view of a kiln with certain of the layers removed to show the manner of building the same, and showing the burners in position.

Fig. 8 is a top plan view of a fragmentary part of the kiln, showing the manner of closing up the arches between unit piles, as is performed in the center of the kiln shown in Fig. 7.

Fig. 9 is a section through a part of the kiln illustrating diagrammatically the manner of making up the kiln; and

Fig. 10 is a plan view of a modified or alternative method of making up the arches from solid unit piles of brick.

According to a well known method of making the green brick, the clay is taken from the pit, tempered, pugged and squirted through a die of single or multiple form onto a cutting table where the longitudinally extruding stream of clay is cut into brick lengths. From thence the green bricks go onto a hacking table, which is generally a belt traveling at a rate of speed greater than the rate of speed at which the clay is extruded from the brick machine, so that the bricks will be separated from each other a short space as they come to the men who take the bricks from the hacking table and pile them upon the transfer or dryer car. A suitable track for the dryer cars runs alongside the hacking table, and in Figs. 1, 2 and 3 I have shown one of the dryer cars of my invention such as is employed for forming unit piles of brick for making up the bottom layers of the kiln.

The car 1 is adapted to run on rails 2 mounted upon suitable ties or other supports such as 3 forming a track. The car 1 comprises a bottom frame 4 having bearing brackets 5 for mounting the axles 6, 6 upon which are secured flanged wheels 7, 7 guided upon the rails 2, 2.

The frame 4 is preferably made of longitudinal and transverse channel bars forming the side and end sills and bolsters respectively. At the corners there are mounted upright posts or stakes 8, 8 preferably made of angle iron having cross bars or plates 9, 9 secured to the stakes or posts 8, 8 at each end and disposed at elevation which will bring them endwise into alignment with tiers of brick in the unit pile 10, as shown in Fig. 1, in which tiers the end faces of the brick may abut against said plates 9, 9. The inside or facing surfaces of the plates 9, 9 are smooth so that the unit piles may be pushed together or consolidated without difficulty.

Short diagonal braces 11, 11 at the corners brace the ends of the car, which are thus formed by the stakes 8 and the cross plates 9, to the side sills of the frame 4.

A series of T-bars, 12, 13, 14 and 15 are

connected between the side sills of the frame 4, these T-bars having their ends riveted to the upper flanges of the angles of the sills, as indicated at 16 and 17 in Fig. 3, the head of the T-bars being placed flat downwardly on the horizontal legs of the angle bars of the side sills, and the webs of the T-bars lying in a transverse vertical plane.

These T-bars brace the frame 4 and in addition serve as guides or ways upon which are mounted a series of inverted channel bars 18, 19, 20 and 21. The channel bars have downwardly extending flanges, and the flanges are notched as indicated at 22, 22 so as to be guided on the upwardly extending flanges of the T-bars.

The channel bars 18, 19, 20 and 21 have their webs perforated by a series of holes 23 for the purpose of permitting hot gases to rise therethrough for drying the bricks mounted upon the same. Preferably these holes are placed between the groups of pickup bricks, as will be apparent from a comparison of Figs. 1 and 4.

Each one of the inverted channels 18, 19, 20 and 21 has two guides 24 and 25 formed of relatively thin spring metal and of substantially the same width as the channel secured thereupon. These guides 24 and 25 comprise a foot member 26 bent at right angles to the main body of the guide for clamping as by means of bolts to the top of the corresponding channel. At their upper ends the guides 24 and 25 have an integral horizontal portion 27, then a vertical portion 28 and a short horizontal portion 29, as may be seen from Figs. 1 and 4. The horizontal portion 27 is of a length approximately one-third brick-length. The vertical portion 28 has a height of approximately one brick width and the upper short horizontal portion has a length preferably slightly less than the thickness of a brick. These dimensions may vary slightly, but should conform fairly closely for best results.

The guides 24 and 25 on each channel are placed back to back and define between them a pier which separates one arch 30 from the other arch 31. The channels 18, 19, 20 and 21 are of a width substantially equal to one brick-length, and likewise the guides 24 and 25 are of a width substantially equal to one brick-length.

When the car is prepared for hacking bricks thereupon the channels or base plates 18, 19, 20 and 21 are preferably arranged as shown in Fig. 3, that is, the plates 18 and 19 substantially in contact and the plates or channels 20 and 21 substantially in contact, but the plates or channels 19 and 20 are separated by a space which is approximately equal to two inches. If desired, the plates or channels may all be spaced substantially equidistant, but placing the base plates or channels in substantial contact in pairs is

satisfactory to permit drying of the bricks when the car arrives in the dryer.

The car empty and with the channels spaced as shown in Figs. 2 and 3, is run along-
5 side the hacking table and the workmen pile
the brick onto the car 1 to form the unit pile
shown in Fig. 1. The unit pile which is there-
by produced is four brick-length deep hori-
zontally, nine brick-width high and ten brick-
10 length long. It really consists of four piles
closely grouped together, but these four piles
after the car passes through the dryer are
closely pushed together as by means of a crow-
bar applied to the outer one of a pair of the
15 base plates such as 20 and 21 to push the base
plates all closely together so that the four
piles on the four base plates are all in contact
and are more easily handled by the fork
shown in Fig. 5.

20 In piling the bricks onto the cars shown
in Fig. 1 eleven groups of pickup brick are
first set in fours and in alinement on each
of the channel bar base plates. The spaces
such as 32, 33, 34, 35, 36, 37, 38, 39, 40, 41,
25 42 and 43, between adjacent groups of pick-
up bricks or immediately outside of them
are adapted to receive the tines such as 44
of the fork 45. The fork 45 is a well known
30 device employed for this purpose, and in the
practice of my invention in connection with
the unit pile shown in Fig. 1 I employ a four-
teen-tined fork.

It will be observed that between the unit
35 groups 46 and 47 and their corresponding
guides 24 and 25 no pickup bricks are in-
cluded, but that is not necessary. The rea-
son why they are not necessary is simply
40 that there are no bricks above them to be
supported by such pickup bricks, and the
guides 24 and 25 may, therefore, be placed
between adjacent tines of the fork. It will
be observed that the foot member 26 is pref-
45 erably of a length approximately equal to
twice the thickness of a brick so that these
guides will not in any wise interfere with
the introduction of the tines of the fork into
the spaces between pickup bricks.

It will also be observed that of the groups
50 46 and 47 the two innermost bricks of the
groups have nothing resting upon them and
therefore are not essential to supporting the
unit pile of brick above them. They are use-
55 ful, however, to fill up the space between the
tines since the tines 44, 44 have upon them a
series of laterally moving gripping fingers
50 which are projected laterally when the
weight of the unit pile comes upon the tines
44 for picking up with the unit pile the group
of pickup brick upon which the unit pile
60 rests.

The fork 45 employed for lifting the unit
pile from the car 1 shown in Fig. 1 has four-
65 teen tines. It will be observed that between
the fourth and fifth tine and the tenth and
eleventh tine the pickup bricks are not em-

ployed since the arches come at this point.
The additional pickup bricks, which form
part of the third and ninth groups, may be
removed after the unit pile 10 has been picked
off of the car 1 and deposited in the kiln. I
70 have found in practice that it is not necessary
to remove the loose pickup bricks except at
the outer ends of the kiln. They are removed
by racing them out of the open ends of the
75 arches.

Each group of pickup bricks for a single
80 section of the unit pile comprises four bricks
placed edgewise two bricks wide and two
bricks high, with the length of the bricks
transverse to the base plates or channels,
such as 21.

These pickup bricks comprise two layers
or tiers. The next tier, that is, the third
counting upwardly, comprises bricks dis-
posed transversely to the pickup bricks and
extending longitudinally. The guides 24
and 25 accurately define the pier which is
formed between arches, and the end plates
9 define the limit of outward setting of the
longitudinally arranged bricks for each of
90 the four vertical sections of the unit pile.
The fourth, fifth and sixth tiers are piled
three on three.

The seventh pile is also mainly three on
95 three, but it will be observed that between
the outermost three bricks disposed longi-
tudinally, namely 51 at the left and 52 at the
right, a single brick as at 53 and 54 is laid
100 crosswise before the next longitudinal bricks
are placed. This is done to project the lon-
gitudinally disposed bricks 55 and 56 out over
the edges of bricks below the same to close in
the top of the arch. This building of the
105 bricks inwardly toward each other is termed
"jetting" or turning of the arches.

Upon the opposite side of each arch like-
wise a single transverse brick 56 and 57 is
interposed between longitudinal bricks so as
110 to bring the bricks 58 and 59 likewise over
the bricks below them to turn or jet the arch
from the pier. The upper end of the guides
24 and 25 define the placing of the bricks 58
and 59 so that the work of the men at the
115 hacking table is greatly facilitated.

The eighth and ninth tiers of brick are next
laid and these tiers, it will be observed, are
so disposed as to bring the bricks 60 and 61
lengthwise over the gap between the bricks
55, 58 and 59, 55 respectively. Also the bricks
120 on each side of the bricks 60 and 61 are dis-
posed longitudinally in order that the bricks
55, 58 and 59, 55 shall be held in a relatively
firm mounting like cantilever beams for sup-
porting the bricks 60 and 61.

The top layer has longitudinally disposed
bricks at the ends bearing against the end
guards or plates 9 and has two bricks end to
end at the center, and the remainder of the
tier comprises transversely disposed bricks.

125 After the car 1 has been filled it is then
130

passed on and pushed into the dryers where the bricks are subjected to hot gases for drying, the arrangement of the separate channels or base plates 18, 19, 20 and 21 and the 5 perforations through these plates facilitating the passage of hot gases up along the sides of the bricks for drying the same to facilitate burning. After the cars pass through the dryer a workman inserts a bar between 10 one of the side frames and the outer one of the base plates or channels and forces the channels with the bricks piled upon them sidewise as close together as possible so that the unit pile is compacted crosswise of the 15 car.

Thereupon the lifting fork 45 is brought into position with the tines 44 of the fork in register with the spaces between pickup bricks. The fork comprises a substantially 20 U-shaped frame with one side of the U forming the tines and the upper side of the U forming a frame, as indicated at 63 in Fig. 5. This U-shaped frame being suspended as on the links 64 and 65 on a turntable frame 66, 25 which is mounted as by means of the ball bearings 67 upon an upper frame 68 carried by the crane mounted in an overhead position, as indicated in dotted lines in Fig. 7 at 69, the upper frame 68 being connected to the car 70 which is adapted to move longitudinally of the crane 69 and transversely to the 30 length of the kiln. The overhead crane 69 travels on the overhead longitudinal tracks 71, 72 mounted on top of the posts 73 and 74 placed at the sides of the kiln. These posts also preferably support a suitable roof. The crane 69 traveling on the tracks 71 and 72 longitudinally has the crane car and hoisting mechanism 70 connected to the turntable 35 frame 68 so that the fork may be brought to any position within the kiln space, and due to the swivel or turntable construction, as shown in Fig. 5, the fork may be turned into any angular position desired.

40 The car 1 shown in Fig. 1 is employed only for producing unit piles with transverse arches 30, 31 therethrough to be used in forming the lowermost layer of unit piles in constructing the kiln indicated generally in Fig. 50 7. In taking the unit piles 10 shown in Fig. 1 from the car 1 the fork is inserted between the pickup bricks and the crane then raises the fork, whereupon the fingers 50 are projected from the sides of the tines, and grip the lowermost pickup bricks by laterally applied pressure, and then the entire unit pile is raised off of the car.

Since the guides 24 and 25 are pushed together edgewise, they do not present any 55 opening into which the ends of the fingers 50 could be projected in lifting the pile. If the top edge of one of the tines should inadvertently catch on the short horizontal ends 29, 29 of the guides 24, 25 they are easily dislodged by bending the guides or pushing them

away, these guides being preferably formed of spring metal so that they may be readily bent without assuming a permanent set. In piling the brick into the kiln the unit piles 10 with transverse arches in them are set 70 upon the kiln floor, as shown in Fig. 7. First a unit pile such as 75 is set at one corner of the kiln with the longitudinal axis of the pile extending longitudinally of the kiln floor and with the arches 30 and 31, which are formed 75 therein, disposed transversely of the kiln floor. Thereupon a series of unit piles such as 76, 77 and 78 are set upon the floor in contact with each other and all with their arches 80 in alinement. Likewise upon the opposite side of the kiln floor and beginning at one corner there will be placed a similar series of unit piles beginning at the outer end and set inwardly towards the center. The reason for setting in this manner is because the track 85 71, 72 for the crane 69 does not permit the crane car 70 and hence the fork 45 to be carried beyond the line of the track on either side, and hence to fill the entire kiln floor as full as possible it is necessary to start piling 90 at the outer edge and pile inwardly. In the instance shown in Fig. 7, there are four unit piles 75, 76, 77 and 78 on the left hand side, and likewise there are four unit piles on the 95 right hand side, leaving a space between them substantially ten brick-lengths wide.

This space is necessary to permit withdrawal of the fork from the innermost unit pile after it is set. This center space is then filled with solid unit piles, that is, unit piles 100 having no arches formed therein when the bricks are hacked onto the car. For forming the unit piles placed in this center space, cars having the plates or pallets 18, 19, 20 and 21 without guards 24 and 25 thereupon are employed, and solid unit piles are hacked onto the cars, dried, compacted, lifted with the fork and deposited in the center. The outermost pile in the center part of the lowermost layer of the kiln indicated at 80 is of only 110 two brick-lengths in thickness such as would be provided by piling the bricks on two of the pallets or base plates such as 20 and 21, and this half unit pile 80 is set with its innermost edge in line with the adjacent edge of 115 the arch 30 and with its outermost edge in line with the edges of the trunnelled piles 75, 76, 77 and 78, and like trunnelled piles on the right hand side as viewed in Fig. 7.

The next unit pile 81 which is put in the 120 center space between the tunnelled piles, is of four brick-lengths in horizontal thickness, and so likewise are the remainder of the piles 82, 83, etc.

After the central piles such as 80, 81, 82 125 etc. are set into place, workmen with extra dried bricks turn the arches by the following operation, as illustrated in Fig. 8, and as disclosed and claimed in my copending Patent No. 1,773,827, aforesaid, that is to say, a 130

layer of brick on edge is projected out transversely overhanging the space 84 between the two piles 80 and 81, this space 84 between the piles being in alinement with the arch 30.

5 Likewise from the pile 81 a row of bricks on edge is projected out transversely over to close off the top of the arch. These bricks such as indicated at 85 and 86 on opposite sides of the space 84, extend outwardly an 10 amount substantially equal to the thickness of a brick, and then a row of brick as indicated at 87 arranged end to end is laid back of the bricks 84. A similar row of bricks 87 end to end is set back of the bricks 86 to fill 15 in the space which is left by the advance of the bricks 86 out over the edge of the pile.

In the lower right hand corner of Fig. 8 the operation of jetting these bricks out in order to turn the arches is shown in process. 20 That is to say, the bricks 88 and 89 are shown as pulled out from the position formerly occupied by them, and bricks 90 and 91 as being placed back of the bricks 88 and 89. In this manner arches are formed as 25 continuations of the arches 30 and 31 in the unit piles 75, 76, 77, and 78 and so on entirely through the bottom layer of unit piles in the kiln. In this manner the entire lower layer of the kiln is completed with arches 30 running transversely thereacross. It will be noticed that the space between piles such as 80, 81 or 81, 82 and the like are not completely closed over in the lower layer, but that a space as shown in Figs. 7 and 8 is left 35 in the topmost tier of bricks of the unit piles 80, 81 etc. When the next layer of unit piles is placed on top of the lowermost layer or tier of piles, these unit piles above the lowermost layer or tier are all solid unit piles. 40 The pickup bricks of the solid piles span the space remaining between the piles such as 80, 81, 82 and the like, and complete the arch thereby.

The unit piles of the second layer or tier 45 in the kiln are indicated at 93, and they may be set in any desired position so long as they bridge over the arches between piles 80, 81, 82, etc. Thereafter additional layers or tiers of unit piles of brick without arches, as indicated at 94, are set in place in any desired or usual manner to bring the kiln by successive layers or tiers to the desired height.

Thereafter the outside of the kiln is scoved as, for example, by piling a single layer of 50 burned brick or brick stacks around the outside of the kiln except in line with the arches, and daubing the same with a suitable sealing material which may be clay and brick dust. The outer layers of the kiln may have powdered coal incorporated therein to assist in 55 making up the loss of heat due to radiation, as is well known in the art. Dog houses may be built out from the arches to receive the burners indicated at 95 and 96 at opposite ends of the arches so as to bring the flame

from these burners in contact with the outermost layers of the brick of the kiln. The burners 95 and 96 are supplied with suitable fuel, for example, oil and steam or oil and air, as by means of a pair of manifolds 97 and 98 running along the kiln shed. Suitable branches from each of the pipes 97, 98 extend to the burners where valves are provided for the control of the relative proportion and for the total quantity. In burning the brick the burner endeavors to keep the arch filled from end to end with hot gases or products of combustion, which is termed fire, so that the entire bottom of the arch may, when the burning has progressed to the point of getting the lower layers hot, be subjected to full fire and the kiln then burned rapidly.

Usually it takes a progressive heating along the arches to get the bottom layers hot, 85 and it is to be observed that with the single brick-length arches of my invention it is much easier to get the bricks hot with progressive burning from the outside towards the center than has been the case heretofore 90 where arches are of a width greater than a brick-length. As a result the fire may be made to penetrate the lower layers of the kiln more rapidly than has heretofore been possible, and the saving in time of burning is 95 of great importance. Whereas it has taken about 76 hours heretofore to burn a kiln of brick set with arches of the usual size, it is now possible with a kiln of my invention to reduce the burning time to about 48 hours. 100

The saving in labor by having the narrow arches is also of great importance. While I use a greater number of arches, that is, in a kiln of approximately one million bricks, it was customary previous to my invention to provide substantially twenty-five arches. According to my present invention I employ about thirty arches, but because of the much smaller number of bricks to be set by hand, several workmen may be dispensed with. It 110 was previously necessary in setting the arches for the workmen to handle about four thousand bricks to the arch, while by my invention it is necessary to handle only about one hundred bricks for each arch where the arches 115 are constructed as shown in Figs. 7 and 8.

As an alternative form of making the single brick-length arch, I may employ only solid piles as at the center of the kiln shown in Figs. 7 and 8, and construct the arches by setting the piles all transversely of the floor, as indicated in Fig. 10 in the lowermost course of the kiln, separating the solid piles such as 100, 101 and 102 by spaces for arches, which spaces are indicated at 103 and 104 in Fig. 10 of a single brick-length in width.

Then the turning of the arches by jetting out the bricks is the same as shown in Fig. 8. Thereafter the second layer is set as shown in Fig. 9, and so on up through the rest of 130

the kiln. In this alternative form of setting the lowermost layers it is not necessary to preform the arches in the unit piles, and hence all of the unit piles may be hacked on cars without guides such as 24 and 25.

While I have shown in Fig. 7 the two methods of forming the arches in combination, it is to be understood that either method may be practiced alone if desired, but in the event 10 that the preformed arches are employed throughout the lowermost layer of the kiln, space must be provided along one side of the kiln for withdrawing the fork. This is possible in many installations where there is a 15 loading shed alongside of the kiln floor and the crane is employed to span both the kiln floor and the loading space.

I do not intend to be limited to the details shown and described.

20 **I claim:**

1. In combination, a platform for supporting a unit pile of bricks, said platform having a pair of upwardly extending guides for guiding the pile of bricks to form arches outside of them and a pier between them.

25 2. In combination, a platform for supporting a unit pile of bricks, said platform having end guides for defining the ends of the unit pile, and a guide between the end guides for defining a transverse arch in the pile.

30 3. In combination, a truck having a platform for supporting a unit pile of bricks, said platform having guides along the ends thereof for defining the ends of the unit pile, and an open guide disposed on the platform between said end guides for defining one side of a transverse arch through the unit pile.

35 4. In combination, a platform of greater length than width for supporting a unit pile 40 of bricks, and a plurality of spring metal guides for guiding the piling of bricks thereupon to define transverse arches through the pile.

45 5. In combination, a plate or platform for supporting a unit pile of bricks, said plate having a pair of spring guides extending upwardly therefrom, said plate being substantially ten brick-lengths in length and substantially one brick-length in width, said guides comprising each a longitudinal portion extending vertically not less than six brick-widths in height, and having a horizontal portion above said vertical portion.

50 6. In combination, a plate having a pair of 55 spring guides extending upwardly therefrom, said plate being substantially ten brick-lengths in length, and substantially one brick-length in width, said guides comprising each a vertical portion not less than six brick-widths in height, and having a horizontal portion above said vertical portion substantially one brick-width in length.

7. In combination, a plate having a pair of spring guides extending upwardly therefrom, said plate being substantially ten brick-lengths in length, and substantially one brick-length in width, said guides comprising 70 each a vertical portion not less than six brick-widths in height, and having a horizontal portion above said vertical portion substantially one brick thickness in length, a short vertical portion above said horizontal 75 portion of substantially one brick-width in length, and a short horizontal portion at its extreme upper end of substantially a brick thickness in length.

8. In combination, a plate having a pair of 80 spring guides extending upwardly therefrom, said plate being substantially ten brick-lengths in length, and substantially one brick-length in width, said guides comprising each a vertical portion not less than six 85 brick-widths in height, each of said guides having a foot portion secured to the plate of approximately two brick thicknesses in length.

9. In combination, a platform substantially 90 ten brick-lengths long, having end guides approximately nine brick-widths high, and having two spring guides four brick-lengths apart along their major portion and having shoulders four brick-lengths 95 and two brick-widths apart at their upper ends, said shoulders defining the upper ends of arches when bricks are piled onto the platform.

10. In combination, a platform substantially 100 ten brick-lengths long having end guides approximately nine brick-widths high, guides on the platform for defining two transverse arches in a unit pile of bricks on the platform, and a fourteen-tined lifting 105 fork for lifting the pile clear of the guides.

11. In combination, a platform substantially ten brick-lengths in length having end guides substantially nine brick-widths high, a pair of guides for forming arches symmetrically disposed on the platform and having their main portions separated by a distance substantially equal to four brick-lengths for defining a pier between them, said pier having five sets of pickup brick in 115 the lowermost course thereof, the pile of brick having arches adjacent the guides and on opposite sides of the pier, the outside of the arches being defined by half-piers each substantially two brick-lengths in width and supported each by three sets of pick-up brick in the lowermost tier, and a fourteen-tined fork for embracing the eleven sets of pickup 120 bricks and for lifting them clear of the guides.

12. In combination, a platform for supporting a unit pile of bricks having pickup 125 bricks in the bottom layer thereof, said platform having end guides and intermediate guides, a fork having tines for engaging the 130

pickup bricks of the pile and for lifting the pile, said guides lying wholly between adjacent tines of the fork.

13. In combination, a platform for supporting a unit pile of bricks, said platform having intermediate its ends upwardly extending guide means for determining the location and form of a transverse arch through the unit pile of bricks.

14. In combination, a platform for supporting a unit pile of bricks, said platform having end guides for determining the length and height of the unit pile of bricks and symmetrically disposed guides between the ends of the platform for defining between them a pier and between said latter guides and the ends, arches extending transversely through the pile of bricks.

15. In combination, a platform for supporting a unit pile of bricks, said platform having end guides for defining the length and height of the unit pile of bricks supported by the platform, intermediate spring guides extending upwardly from the platform and being of less height than the end guides for defining transverse arches through the unit pile.

16. In a device for guiding the formation of a unit pile of bricks and for supporting the same, a channel iron base member of a width approximately equal to the length of a brick and of a length approximately equal to ten brick lengths said channel member having a substantially flat back portion and a pair of arch defining guides comprising a pair of flat spring bars secured upon the back of said channel.

17. In a device for guiding the formation of a unit pile of bricks and for supporting the same, a channel iron base member of a width approximately equal to the length of a brick and of a length approximately equal to ten brick lengths said channel member having a substantially flat back portion and a pair of arch defining guides comprising a pair of flat spring bars secured upon the back of said channel, said guides comprising each a main portion extending substantially at right angles to the back of the channel and a top portion for defining the top of an arch in the pile of bricks.

18. A brick receiving and supporting structure comprising a base frame having longitudinally extending end frames, narrow transverse guides across the base frame, longitudinally extending channel bars having their flanges notched to fit said guides and separate arch defining guides secured to the backs of the channel bars and extending longitudinally and being of a less height than the end guides.

In witness whereof I hereunto subscribe my name this 14 day of May, A. D. 1929.

ARTHUR J. THERRIEN.
